UNITED STATES PATENT OFFICE.

ARTHUR E. DURAM, OF CHICAGO, ILLINOIS.

LIQUID-SEPARATOR AND THE LIKE.

1,255,395.

Specification of Letters Patent. Patented Feb. 5, 1918.

Application filed May 5, 1913. Serial No. 765,540.

To all whom it may concern:

Be it known that I, ARTHUR E. DURAM, a citizen of the United States, residing at Chicago, in the county of Cook and State of Illinois, have invented certain new and useful Improvements in Liquid-Separators and the like, of which the following is a description.

My invention relates to means for removing air or gas from water or other liquid.

The object of my invention is to provide a simple, reliable and highly efficient device of the kind described, wherein a substantially complete separation is secured between water, or other liquid and air or gas.

To this end my invention consists in the novel construction, arrangement and combination of parts herein shown and described, and more particularly pointed out in the claims.

In the accompanying drawings, wherein like or similar reference characters indicate like or corresponding parts:

Figure 1 is a vertical longitudinal section of one form of my device.

Fig. 2 is a similar view of a slightly modified form.

Fig. 3 is an elevation of still another form of my device with parts removed and broken away to more clearly show the construction of my device.

In the form shown in Fig. 1 of the drawings, 1 is a commingler having a steam inlet 2, and a water inlet so arranged that the water entering the commingler will fill the chamber 4 and escape into the central steam passage 5 through the several orifices 6—6 thus condensing the steam passing into the commingler and at the same time raising the temperature of the water which issues from the outlet opening 7. When thus arranged it is well known that more or less air or gas is entrained in the steam, and water entering the commingler through the inlet pipes 2 and 3 will be discharged therefrom with the hot water. It is the purpose of my present invention to provide a simple and efficient means for eliminating the air or gas from the water so that the water may be satisfactorily employed for heating or other purposes.

In the form shown in Fig. 1 my device consists of a reservoir 8 of ample capacity and a receptacle 9 positioned within the reservoir. The reservoir 8 may be provided with a loose cover 10 to prevent dust and

other foreign matter from entering the reservoir, a suitable opening or vent 11 being provided to prevent the free escape of air or gas. The receptacle 9 is rigidly secured 60 in position within the reservoir and is preferably open at its upper end. The upper edge of the receptacle is positioned slightly below the water line which it is desired to maintain in the reservoir. The outlet pipe 65 7 of the commingler extends substantially vertically into the receptacle 9 preferably near its center with the lower end of its outlet pipe positioned well below the desired surface of the liquid in the receptacle. The 70 receptacle 9 may be secured in position in reservoir in any desired manner. In the form shown, a plurality of legs or braces 12—12 are rigidly secured to the walls of the receptacle and extend to the walls of the reservoir to which they are also rigidly attached thereby preventing any movement between the receptacle and reservoir and maintaining a broad open passageway between their walls and bottom surfaces. The 75 commingler 1 is preferably provided with a flange 14 or other convenient means for rigidly attaching it to the cover 10 to maintain the relation between the several parts of the device. An outlet pipe 15 is also provided attached in any suitable manner to the bottom of the reservoir 8 so that liquid entering my device will be discharged into the receptacle 9 whence, it passes upward and over the edge of the receptacle into 80 the reservoir 8 thence it flows slowly downward to the bottom of the reservoir and out through the pipe 15. A suitable valve 16 is preferably provided in the water inlet pipe 3 of the commingler to control the admission of liquid and to maintain the desired 85 height of water in the reservoir. It is obvious that when thus constructed a mixture of water and air or gas discharged into the receptacle will first rise comparatively rapidly to the top of the receptacle where it will lose substantially all of its velocity and pass slowly in a broad shallow stream over the top of the receptacle where any air or gas entrained in the water is brought to 90 the surface and escapes, the liquid passing slowly downward to the outlet pipe substantially 95 free from all air or gas.

In all cases however, I arrange to reduce the velocity of the fluid escaping from the 110 receptacle to the lowest possible point and bring the liquid as it passes out of the recep-

tacle into as intimate contact as possible with the free air, and this is accomplished preferably by maintaining the water level in the reservoir substantially at the upper edge of the receptacle 9.

In the form shown in Fig. 2 the reservoir 8 and receptacle 9 are arranged substantially as hereinbefore described, except that instead of the commingler extending downward into the receptacle an inlet pipe 20 is provided extending through the wall of the reservoir and into the side of the receptacle. In this form the liquid entering the receptacle will have no downward tendency but will lose its velocity as it passes over the wall of the receptacle substantially as hereinbefore described.

If desired suitable automatic mechanism may be provided for controlling the height of the fluid in the reservoir. In the form shown an arm 22 is pivotally attached to the wall of the reservoir 23. A float 24 is attached to the free end of the arm. A lever 25 is also attached to the reservoir as by the bracket 26, one end of the lever 25 is connected by a link 27 to the arm 22 so that movement of float 24 will produce a corresponding movement in the lever 25 the opposite end of the lever 25 is connected by a rod 28 to an arm 29 arranged to control a valve 30 on the inlet pipe 20 so that the movement of the float will operate the valve 30 to maintain a constant water level in the device.

35 In the form shown in Fig. 3 a fluid tight casing 35 is provided having an inlet pipe 36 at one end and an outlet pipe 37 at the opposite ends. A transverse partition 38 is provided extending from the bottom of the 40 casing upward to the water level it is desired to maintain in the casing. A shelf 39 is preferably arranged across the casing at the upper edge of the partition. In this form a suitable valve 40 is provided in the inlet 45 pipe 36 having an arm 41 connected to the free end of the arm 43 of a bell-crank 43-44 having its axis extending through a suitable fluid tight bearing in the wall of the casing 35. The arm 44 of the bell-crank is within 50 the casing and is connected by a rod 45 to the arm 46 of a bell-crank 46-47 mounted within the casing and having a float 48 attached to the free end of the arm 47 of the bell-crank. The several parts are so arranged

that the movement of the float 48 will control the valve 40 to maintain the desired water level in the shell. A suitable air valve 50 is provided above the water level so that any accumulation of air within the shell may be discharged when desired, or if preferred the valve 50 may be suitably connected to the float 48 or if preferred left slightly open to allow a constant leakage sufficient to prevent air locking in the device. 55 60

Having thus described my improvement 65
it is obvious that various immaterial modifications may be made in my device without departing from the spirit of my invention, hence I do not wish to be understood as limiting myself to the exact form or construction shown. 70

What I claim as new and desire to secure by Letters Patent is:

1. In a device of the kind described, a reservoir having an outlet, in combination with a receptacle positioned within said reservoir and arranged to receive all liquid passing therethrough, means for directing the fluid toward a side wall of said receptacle, the walls of said receptacle extending upward into close proximity to the surface of the liquid in said reservoir and adapted to force all liquid passing through said reservoir to the surface of the liquid in the receptacle, the several parts being so proportioned that the liquid will lose the greater part of its velocity before it escapes from said receptacle. 75 80 85

2. In a device of the kind described a reservoir having an outlet and a receptacle 90 open at the top positioned in said reservoir and rigidly attached to the walls thereof, the top of said receptacle being substantially at the level of the liquid in said reservoir, in combination with means for directing a fluid 95 into said receptacle against one wall thereof, the several parts being so proportioned that the liquid entering said receptacle will lose the greater part of its velocity before it escapes from said receptacle. 100

In testimony whereof, I have hereunto signed my name in the presence of two subscribing witnesses.

ARTHUR E. DURAM.
